G. ARTHUR.
ELECTRIC WATER HEATER.
APPLICATION FILED JULY 6, 1918.

1,309,234.

Patented July 8, 1919.

UNITED STATES PATENT OFFICE.

GUY ARTHUR, OF RITZVILLE, WASHINGTON, ASSIGNOR TO ARTHUR-FOWLER CO., OF RITZVILLE, WASHINGTON, A CORPORATION OF WASHINGTON.

ELECTRIC WATER-HEATER.

1,309,234.

Specification of Letters Patent.

Patented July 8, 1919.

Application filed July 6, 1918. Serial No. 243,648.

To all whom it may concern:

Be it known that I, GUY ARTHUR, a citizen of the United States, residing at Ritzville, county of Adams, and State of Washington, have invented new and useful Improvements in Electric Water-Heaters, of which the following is a specification.

This invention relates to improvements in circulating water heaters of the electrical 10 type.

One of the objects of this invention is to provide an insert electric heater adapted to be disposed in a water tank and constructed to contain the water to be heated, or admit 15 the same, cold, and then discharge the heated water at a point remote from the point of admission, thereby causing a circulation of water in the tank in effecting the heating of the water.

20 In the most improved embodiment, my device is in the form of a tubular heating means which is proportioned to extend vertically substantially throughout the length of a water tank, the tubular means having 25 an intake adjacent to the lower portion of the tank and an outlet adjacent to the upper portion of the tank so that as the water is heated in the tubular means, it rises to the top of the tank and discharges thereinto.

30 Water tanks for household use are provided with a cold water inlet and a hot water outlet and the device of my invention is especially designed for this type of tank. However, it is a feature of my invention to 35 provide means whereby hot water may be drawn off directly from the tubular means, as well as through the usual hot water outlet pipe.

In the most improved embodiment, my invention 40 comprises an inner heating tube surrounded by an outer protecting tube with a suitable intervening air space between the tube and pipe. At one end, the tube and pipe are connected in a manner to render 45 it impossible for water to enter between the same, and at the remaining end, a suitable packing device is provided whereby one tubular member may move with respect to the other, to take up for difference in expansion, the packing device likewise being a 50 water-tight connection. Interposed between the pipe and tube, is a heating coil having a novel mounting on the tube whereby the heat of the coil is practically concentrated 55 on the tube and is prevented from radiating

to any appreciable extent upon the pipe, the intervening air-space assisting in the performance of this function.

Other novel features and objects of my invention will be more fully described in connection with the accompanying drawing and will be more particularly pointed out in and by the appended claims.

In the drawing:

Figure 1 is a vertical sectional view of a 65 water tank such as is common in domestic households and illustrating the application of the device of my invention thereto.

Fig. 2 is an enlarged contracted sectional view of the device of my invention. 70

Fig. 3 is a detail sectional view on line 3—3 of Fig. 2.

Like characters of reference designate similar parts throughout the different figures of the drawings. 75

As illustrated, 1 designates a typical form of water heating tank, for which my invention is designed, the tank having a bottom 2 and a top 3. The top 3, of a tank of this type, is usually provided with a threaded bore 4, for insertion of the usual cold water feed pipe which extends downwardly in the tank to a point near the bottom 2. These tanks are also provided with an additional threaded bore 5, in the bottom 2, for a cold 80 water inlet, and with a threaded bore 6 in the top for a hot water outlet. In installing my improved device, which is generally indicated at 7, I remove the cold water pipe and substitute the device of my invention, 85 connecting the tank 1 for cold water supply by a pipe 8. The hot water drawoff is indicated at 9 and this need not be altered. The foregoing relates specifically to the application of my invention to this particular 90 type of tank but it will be understood that my invention is not limited to this particular utility.

As shown, my invention includes an inner heating tube 10 which is formed of very thin material of a character to efficiently 100 conduct heat. Surrounding the heating tube 10, and preferably in concentric relation with respect thereto, is a protecting pipe 11. The size of the tube and pipe, as 105 regards the diameter thereof, is such that an intervening air-space 12 is formed therebetween.

A heating coil 13 is wound about the tube 10, in the intervening space 12. In the spe- 110

specific form shown, the tube 11 is peripherally covered with a very thin and preferably hard electrically insulating material which is also a good conductor of heat. I prefer to use mica, as indicated at 14. It is highly advantageous to arrange the convolutions of the heating coil so as to render it impossible for the same to get into sufficient proximity to cause a short circuit, and it is a feature of my invention to dispose a soft insulating material over and about the mica so that the coil, which is composed of bare wire, can be wound sufficiently tightly about this soft insulating material to embed therein. I have found that hot water flax packing, as indicated at 15, sufficiently performs this function because it is also a good conductor of heat as well as being an electric insulator. Thus it will be seen from Fig. 3, that the bare wire forming the coil can be wound sufficiently tightly on the soft flax packing to embed therein in a manner to dispose the wire very close to the mica. In fact, the bare wire is shown flush with the periphery of the soft packing, which is possible although not absolutely necessary. Finally, I cover the bare wire with soft insulating tape 16, or any other insulating material which is a poor conductor of heat. With this construction, in addition to the air space 12, it will be seen that practically all of the heat from the coil 13 will be localized on the heating tube 10. Furthermore, the tape 16 will function in addition to the soft packing 15, to prevent the convolutions of the coil from getting out of position.

In cases where the device of my invention is used in connection with a closed water tank, as illustrated, I provide a novel form of water-tight connection between the pipe and tube, 11 and 10, respectively, embodied in a fitting structure adapted to have threaded connection with the wall portion of the tank.

As illustrated, a fitting 17 of tubular form is exteriorly threaded, as indicated at 18, and is adapted to be turned into position in the threaded bore 4, of the head 3, to dispose the heater inside the tank. The lower portion of the fitting 17 is reduced to provide an annular seat for the upper end of pipe 11, as indicated at 19. The pipe 11 will be suitably secured in water-tight engagement to said annular seat 19. The upper end of heating tube 10 projects into the fitting 17 and a suitable head 20, may be bored, as shown, to form a water-tight connection between the tube 10 and the fitting 17 and to securely hold the tube 10 to the fitting 17. A hot water discharge outlet 21 forms constant communication between the upper end of tube 10 and the upper portion of the tank 1. An opening 22, in the upper portion of the head, permits 23 of withdrawal of hot water directly from

the tube 10 upwardly through the fitting 17. The upper end of the fitting 17, exteriorly of the tank, is provided with a suitable angle union 23 from which a pipe 24 leads. Flow through the pipe 24 may be controlled by a suitable cock not shown. It will be understood that my improved device is adapted for use as an instantaneous heater as well as a tank heater and therefore I consider it within the scope of my invention to either draw the hot water from the tank through pipe 9, or pipe 24.

Now it will be clear that the upper end of the protecting pipe 11 and the upper end of the tube 10 are both securely fixed to the fitting 17. By reason of the fact that the protecting pipe 11 will always be at a lower temperature than tube 10, I therefore provide means for taking care of unequal expansion, such means preferably being at the lower end of the pipe and tube.

As illustrated, the lower terminal of the tube 10 is slightly above the terminal of the pipe 11. An upper packing nut or abutment 25 may be threaded into the interior of pipe 11. Such nut 25 is provided with a smooth bore for contact with the periphery of tube 10. Packing 26 will be compressed between the tube 10 and pipe 11 by means of a lower packing nut 27. This lower packing nut 27 likewise has threaded connection with the interior of pipe 11 and a smooth bore fitting about the periphery of tube 10 so that the tube may contract or expand freely as regards the nuts 25 and 27 and the packing at all times will maintain a water-tight connection to prevent water from entering the intervening space 12.

If the rate of the flow of the water upwardly through the heating tube 10, as a result of the heating action of the latter, is relatively rapid, then the water will not be heated to as high a temperature as though the flow was restricted. Therefore I provide means for restricting the rate of flow upwardly through the tube 10.

In the specific form shown, a rubber washer 28 of a diameter substantially equal to the internal diameter of pipe 11, is disposed in position shown with the washer 115 abreast of the terminal end of the tube 10. The lower packing nut 27 serves as an upper abutment for the washer and a washer holding nut 30, having an enlarged bore 31, is threaded into the pipe 11 to 120 clamp the washer 28 into position shown. If desired, the washer 28 may be clamped into engagement with terminal end 29. However, the main function of the washer 28 is to provide a restricted flow by means 125 of the relatively small aperture 32. The rate of flow can be fixed by substituting washers having apertures of different sizes. For instance, if it was desired to heat the water to a very high temperature, a washer 130

of the very small aperture would be provided, and for a relatively lower temperature, a washer with a relatively larger sized aperture would be provided. I preferably 5 use a rubber washer because lime does not encrustate on rubber and therefore the aperture would always remain open, and of its initial size.

10 The terminals 33 and 34, of the heating coil, are diagrammatically shown as passing upwardly through the fitting 17, the specific manner in which these terminals are protected not being a feature of this particular application.

15 It will be seen that the protecting pipe 11 protects not only the tube 10 but the heating coil 13 from direct cooling influence of the body of water in the tank 1, and therefore, practically the entire heat 20 from the coil 13 may be localized upon tube 10 without any cooling action whatsoever.

By making the device of my invention 25 in the form of an insert, I can provide a very small heating tube 10, in view of the fact that the latter extends practically co-extensive with the length of the tank, and at the same time, I present to the water in the tube 10 a relatively extensive heating area. Thus while the water in the main 30 body of the tank may be cold, hot water will be delivered through opening 21 into the top of the tank and by reason of the circulation in the tank, the contents of the latter will be very quickly heated.

35 It is believed that the utility and advantages of my invention will be clearly understood by the foregoing description, and while I have herein shown and described one specific form of my invention, I do 40 not wish to be limited thereto except for such limitations as the claims may import.

I claim—

45 1. An electric water heater for closed water heating tanks, comprising in combination, a water heating tube having an intake opening near the bottom of said tank and an outlet discharging near the top of said tank, a protecting pipe of enlarged diameter 50 with respect to said tube and said pipe having watertight connection with said tube to form an intervening air-chamber, the exterior of said tube inside of said pipe being covered with a heat conducting and electrical insulating material of a thin hard nature, a soft insulating material covering said hard material, a heating coil of bare wire tightly wound about the soft insulating material to embed therein, and a non-heat conducting 55 and electrical insulating material covering said bare wire and in spaced relation from said protecting pipe to afford an air space whereby the heat therefrom will be directed 60 radially inwardly against said heating tube, substantially as described.

2. In combination, a water heating tank having a cold water inlet pipe opening into the bottom of said tank and a hot water outlet pipe leading from the upper portion of said tank, a water heating tube device 70 fixed in said tank and having a cold water inlet disposed at the lower portion of said tank and a hot water outlet near the top of said tank whereby the water admitted to the lower end of said tube will be heated 75 and rise and be discharged into the upper end of said tank, and being constructed for drawing off hot water exteriorly of the tank and directly from said tube device, substantially as described.

3. In combination, a water tank, and an electric water heater comprising an inner heating tube and an outer protecting pipe, a fitting adapted to be fixed in the wall of said tank and having water-tight connection with said pipe to support the heater, a head fixed in said fitting and having water-tight connection with the end of said tube, and a discharge outlet opening to the tank and extending from the inner tube out 85 wardly through said head and fitting, substantially as described.

4. In combination, a water tank, an electric heater therefor comprising a tubular fitting adapted to be fixed to the wall of the 95 tank and having a hot water draw off exteriorly of the tank, a protecting pipe having water-tight connection with the interior end of said fitting, a head having watertight connection in the interior of said fitting, a 100 water heating tube in said pipe having water-tight connection with said head, said head having an opening for discharge of hot water from said tube directly through said fitting and out of said tank, and an opening establishing communication between the said tube and the interior of said tank, substantially as described.

5. In an electric water heater, an inner heating tube having an intake end, an outer 110 protecting pipe surrounding said tube in spaced relation therewith and projecting beyond the intake end of said tube, a washer in said intake end having a restricted opening and said washer being of a diameter substantially equal to the interior diameter of said pipe, a packing nut in threaded engagement with the threaded interior of said pipe and in smooth engagement with the exterior of said tube and forming an upper abutment for said washer and a lower packing abutment, a washer nut engaging the opposite face of said washer and holding the latter against said lower packing nut and the terminal edge of said tube and having 115 threaded engagement with the interior of said pipe, a packing filling the space between said pipe and tube above said lower packing nut for a slight distance, and an abutment above said packing nut whereby the 120 125 130

4
packing may be tightly clamped in place to form a water-tight connection between said pipe and tube, substantially as described.

6. In an electric water heater, an inner 5 heating tube having an intake end and a discharge end, a coil for heating said tube, a pipe surrounding said tube, means forming a rigid and water-tight connection with said pipe and tube at the discharge end of 10 the tube to prevent water from entering between the tube and pipe, and packing means slidably connecting the intake end of the tube with said pipe to allow for unequal expansion and to prevent water from entering 15 between said tube and pipe, substantially as described.

7. In an electric heater, an inner tube,

having a water intake and a discharge end, a coil for heating said tube, and flow controlling means, interchangeable in said tube, 20 for limiting the rate of flow of the water through said tube to determine the temperature of heat supplied to the water by said tube, substantially as described.

8. In an electric water heater, an inner 25 tube, a pipe surrounding said tube, a heating element therebetween, and packing means slidably connecting adjacent ends of said pipe and tube to allow for unequal expansion and prevent water from entering 30 between said pipe and tube.

In testimony that I claim the foregoing as my own, I hereby affix my signature.

GUY ARTHUR.
